UNITED STATES PATENT OFFICE.

WALTER CURTIS, OF WILLESDEN GREEN, LONDON, ENGLAND.

MEANS FOR CONTROLLING THE ELECTRIC LIGHTING OF MOTOR-VEHICLES.

1,313,583.

Specification of Letters Patent.

Patented Aug. 19, 1919.

Application filed March 2, 1917. Serial No. 151,929.

To all whom it may concern:

Be it known that I, WALTER CURTIS, a subject of the King of Great Britain, residing at 16 Maybury Gardens, Willesden

5 Green, in the county of London, England, have invented certain new and useful Improvements in or Connected with Means for Controlling the Electric Lighting of Motor-Vehicles, of which the following is a specification, reference being had to the drawings hereunto annexed and to the figures, letters, and reference-numerals marked thereon—that is to say:

10 The invention relates to improvements in or connected with means for controlling the electric lighting of motor vehicles.

15 For this purpose a switch is employed consisting of a base of non-conducting material provided with terminals for a number 20 of leads and upon said base plate is revolvably mounted a disk or plate of similar material carrying contacts arranged in such manner as to complete certain electric circuits according to the position of the revolvable disk.

25 In the accompanying drawings:—

Figure 1 is a diagram of the wiring or connections of the switch the dotted lines illustrating the two acting positions of the 30 switch bar.

Fig. 2 is a diagrammatic plan of the base of the switch.

Fig. 3 is a diagrammatic underside view of the revolvable disk or plate.

35 Fig. 4 is a detail view of the means for resiliently forcing the two parts of the switch together.

Fig. 5 is a similar view to Fig. 1 illustrating a modification.

40 Fig. 6 is a plan or top view of the base illustrating the modified arrangement of the terminals.

Fig. 7 is an underside view of the base showing the arrangement of the terminals.

45 Fig. 8 is an underside view of the revolvable disk illustrating the modified arrangement of brushes or contacts and

50 Figs. 9, 10, 11 are diagrammatic views illustrating the various positions of the switch bar relatively to the terminals.

In the several figures like parts are indicated by similar letters of reference.

Referring to Figs. 1 to 4, *a* represents the switch, *b* represents the magneto, *c* represents the accumulator, *d* represents the coil box, *e* represents the head lights, *f* represents

sents the tail light, *g* represents the side lights, *h* represents the chassis, *A* represents a connection with the accumulator *c* and *M* a connection with the magneto *b*.

60

The switch consists of a base *a* of non-conducting material upon which is revolvably mounted a disk or plate *a'* of similar material.

65 The disk or plate *a'* is connected with the base *a* by an axial pin or stud *1* which passes through and is fixed with the base *a*, and said disk *a'* is revolvably mounted upon the pin *1* and is forced toward the base *a* with a resilient pressure by means of a helical 70 spring *1'* coiled around the pin *1* and there adjustably held by a nut *1'* or it might be by nuts screwing upon a thread upon the pin *1* for the purposes of adjustment of the degree of compression of the spring *1'* the nut *1'* serving as an abutment for the spring *1'*.

75 The pin or stud *1* forms a terminal and has connected with it a lead or conductor connecting with one of the side lights.

80 Beneath the revolvable disk or plate *a'* and fixed with it is a switch bar *a''* which is constantly in electric connection with the central pin or stud *1* and upon the face of the base *a* are two suitably spaced stop pins *a''* between which the switch bar *a''* is adapted 85 to work and midway between the stop pins *a''* is a contact *o* which however is not connected with any circuit but which merely represents the "off" position of the switch bar *a''*.

90

Upon the base *a* adjacent to one of the stops *a''* is a terminal *2* with which the switch bar *a''* is adapted to make contact when in that position and in a suitable position also on the base is another terminal *3* 95 with which the switch bar *a''* then also makes contact.

100 Adjacent to the other stop pin *a''* are two terminals *4* and *5* and on the underside of the disk *a'* is a contact plate *a''''* which in the described position of the switch bar *a''* makes contact with both of said terminals *4* and *5*.

105 In a suitable position upon the base *a* are two other terminals *6* and on the underside of the disk *a'* is another contact plate *a'''* which in the described position of the switch bar *a''* makes contact with both of said terminals *6*.

110 The wiring connections are diagrammatically represented at Fig. 1 and are such that in the described position of the switch bar *a''* the two head lights *e* of the car are sup-

plied with current from the magneto b in series while the two side lights g and the single tail light f are fed from the accumulator c in parallel.

- 5 In the opposite extreme position of the switch bar a^2 the contact plates a'^x, a'^{xx} are out of action and the switch bar a^2 makes contact with terminals 1 and 5 only whereby the head lights e are cut out and the 10 two side lights g and tail light f are placed in circuit with the magneto b in series thereby saving the current of the storage battery or accumulator c .

In the central position of the switch bar 15 a^2 no circuit is made so that all the lights are cut out. In the example given at Figs. 5 to 11 is illustrated a modification of the device hereinbefore described.

According to this example an additional 20 terminal 7 is provided and the terminal 0, which in the previous example was described as being unconnected with any circuit, is in this case permanently electrically connected with the terminal 7 by means of 25 a strip of metal x , or it might be a length of wire or the like, and the terminals 0 and 7 are also permanently connected with the terminal 5 by the same strip of metal or the like x as shown at Fig. 1.

30 The switch bar a^2 is in this case furnished with brushes $a'^x a'^{xx}$ arranged in suitable positions thereon while the contact plates $a'^x a'^{xx}$ of the revoluble disk or plate a' in the previous example are substituted by 35 brushes $a'^x a'^{xx}$ as shown in Fig. 8.

The electrical connections of the device are diagrammatically illustrated in Fig. 5 and the various positions of the switch bar 40 a^2 are illustrated at Figs. 9, 10, and 11.

40 In the position of the parts indicated at Fig. 9 the brushes $a'^x a'^{xx}$ of the switch bar a^2 make contact with the terminals 2 and 3 while the brushes a'^x and a'^{xx} are at the same time in contact with the terminals 4 and 5 and 6 respectively.

45 In this position of the switch bar a^2 five lights are illuminated namely the head lights e off the magneto b in series and the side lights g and tail light f off the 50 accumulator c in parallel.

In the position shown at Fig. 10 the brush a'^{xx} makes contact with the terminal 0 of the base a thus coupling the same up through the switch bar a^2 itself with the 55 central terminal 1 while the brushes a'^x make contact with the terminals 4 and 7 and in view of the metal strip x the terminals 0, 4, 5 and 7 are thus all electrically connected the result being that the 60 head lights e , side lights g and tail light f are all illuminated off the magneto b the head lights in one series and the other lights in another series circuit.

In the position of the switch bar a^2 shown 65 at Fig. 11 the brush a'^{xx} of the switch bar a^2

makes contact with the terminal 5 and through the connecting strip x with the terminals 0 and 7 the result being that the side lights g and tail light f are illuminated from the magneto b in series.

In the positions of the switch bar a^2 indicated by the dot and dash lines y no circuit is made so that all the lights are cut out as shown at Figs. 9, 10 and 11.

It will be understood that the device may 75 be further modified without departing from the principle of the invention.

What I claim as my invention and desire to secure by Letters Patent of the United States is:—

1. In combination, head lamps, side and tail lamps, a generator, an accumulator, a circuit including said lamps, said generator and said accumulator, a switch controlling said circuit in such manner that when it occupies one position, the head lamps are connected in series with the generator and the side and tail lamps are connected to said accumulator in parallel; when in another position, said switch connects all of 90 said lamps to said generator in series parallel, and when in a third position, said switch connects said side and tail lamps to said generator in series, while said head lamps are disconnected from said generator. 95

2. In combination, head lamps, tail and side lamps, a generator, an accumulator, a circuit including said lamps, said generator and said accumulator, a switch comprising contacts and an arm engageable with said contacts and capable of occupying two extreme positions and three intermediate positions said switch controlling said circuit in such manner that when said arm is in one intermediate position, said head lamps 100 are connected in series with said generator, and said side and tail lamps are connected in parallel with said accumulator; when in another intermediate position, all of said lamps are connected in series—parallel to said generator; when in another intermediate position said side and tail lamps are connected in series with said generator and said head lamps are disconnected from said generator and when said arm occupies either 105 extreme position all of said lamps are disconnected from said accumulator and generator.

3. In combination, head lamps, tail and side lamps, a generator, an accumulator, a 110 circuit including said lamps, said generator and said accumulator, a switch comprising contacts and an arm engageable with said contacts and capable of occupying three intermediate positions and two extreme positions, and a conducting strip permanently connected to three of said contacts, said switch controlling said circuit in such manner that when said arm is in one intermediate position said head lamps are connected 115 to three of said contacts, and when said arm occupies either extreme position all of said lamps are disconnected from said accumulator and generator.

3. In combination, head lamps, tail and side lamps, a generator, an accumulator, a 120 circuit including said lamps, said generator and said accumulator, a switch comprising contacts and an arm engageable with said contacts and capable of occupying three intermediate positions and two extreme positions, and a conducting strip permanently connected to three of said contacts, said switch controlling said circuit in such manner that when said arm is in one intermediate position said head lamps are connected 125 to three of said contacts, and when said arm occupies either extreme position all of said lamps are disconnected from said accumulator and generator.

- in series with the generator and said side and tail lamps are connected to said accumulator in parallel; when in another intermediate position, all of said lamps are connected through said conducting strip to said generator in series parallel; when in another intermediate position, said side and tail lamps are connected through said conducting strip to said generator in series and 5 said head lamps are disconnected from said generator and when said arm occupies either extreme position all of said lamps are disconnected from said accumulator and generator.
- 10 4. In combination, head lamps, tail and side lamps, a generator, an accumulator, a switch comprising contacts, and an arm engageable with said contacts and capable of occupying three intermediate positions and 15 two extreme positions, and circuits including said lamps, said generator, said accumu- 20 lator, and said switch, said switch controlling said circuits in such a manner that when said arm is in its first intermediate position the side and tail lamps are connected to the accumulator, in parallel, and when said arm is in the second and third intermediate positions the side and tail lamps are in series with the generator, while the head lamps are in series with the generator in the first and second intermediate positions and disconnected in the third position, and when said arm is in either extreme position all the lamps are disconnected from the generator and accumulator. 25 30 35
- In witness whereof I have hereunto set my hand in the presence of two witnesses.
- WALTER CURTIS.
